UNITED STATES PATENT OFFICE.

LOUIS GATHMANN, OF CHICAGO, ILLINOIS.

UPRIGHT CENTRIFUGAL FLOUR-BOLT.

SPECIFICATION forming part of Letters Patent No. 319,695, dated June 9, 1885.

Application filed September 28, 1883. Renewed May 14, 1885. (No model.)

To all whom it may concern:

Be it known that I, LOUIS GATHMANN, of Chicago, in the county of Cook and State of Illinois, have invented certain new and useful Improvements in Upright Centrifugal Flour-Bolts; and I do hereby declare that the following is a full, clear, and exact description thereof, reference being had to the accompanying drawings, and to the letters of reference marked thereon, which form a part of this specification.

This invention relates to centrifugal separators of that class in which the axis of the rotating beater-drum is vertical, and in which the material is fed in at the bottom and the refuse or unbolted portions of the material are discharged at the top.

The primary object of the invention is to provide a construction by which the rate of speed on the part of the material being operated upon is regulated in its passage upward through the machine.

The improvements herein described consist, primarily, in the combination, with stationary portions of the machine and with the drum carrying the revolving beaters, of stationary blades or wings movably affixed to the inner surfaces of adjacent uprights or stationary parts of the machine, so that by a change in the angle of the inclination of these stationary wings the progress of the material may be accelerated or retarded without a change of the inclination of the beaters or blades upon the drum.

The invention consists, further, in certain features of construction, which will hereinafter be more fully explained, and pointed out in the claims.

In the accompanying drawings, Figure 1 is an elevation of the machine, having a part of the outer inclosing-wall adjacent to the eye removed, and also a portion of the bolting-screen broken away, to reveal the interior of the machine. Fig. 2 is a central vertical section of the machine in the line xx of Fig. 3. Fig. 3 is a horizontal section of the machine through yy of Fig. 2. Fig. 4 is a fragmentary central vertical section in the line zz of Fig. 3. Fig. 5 is a fragmentary horizontal section enlarged, but otherwise corresponding with that

shown in Fig. 3, indicating a construction whereby each of the adjustable blades secured to the uprights of the machine may be operated or moved by hand. Fig. 6 is a fragmentary horizontal section near the bottom of the machine, or, say, at v , Fig. 4. Fig. 7 is a horizontal section showing a preferred form of the outer inclosing-wall. Fig. 8 is a view of one of the adjustable blades detached, showing a desirable mode of its attachment to the rod which passes through the frame of the machine and by which said blade is controlled.

A A is a base, composed in this instance of two parallel beams, from the central parts of which rise two parallel uprights, A' A', on opposite sides of the machine. Said uprights are connected near the base by cross-beams aa , and at the top by cross-beams A². A³ are vertical parts secured to the inner surfaces of the uprights A', or in line with the diameter of the drum.

C is a screen, made in two upright partspherical sections or parts, each composed of a skeleton frame having vertical bars c and circumferential ribs c' . To the inner surface of this frame is fastened the bolting-cloth or screen proper. The screen-frames are fastened removably by their marginal bars c to the posts A³ by screws c' , passing through the said marginal bars into the posts.

Exterior to the screen-cloths are located the spaces D, inclosed by the outer walls, D', which may be constructed of wood or other material, but which are preferably made, as here shown, in skeleton frames, upon which is stretched heavy canvas or similar perforate material, in order that the bolted substance falling in the chamber D may be cooled by admission of air through the canvas in the natural action of the machine. The walls D' are desirably made removable, so as to give access to the screen, and to this end I prefer the construction shown in Fig. 7, wherein the doors are hinged to the uprights A' and meet at their opposite edges, being held by a hook or other suitable fastening.

Near the base of the structure, and resting on the cross-beam a , is a bottom board, E, either circular or rectangular in form, according to the construction of the outer inclosing-

walls, D', and having a vertical marginal rim, E', of a few inches in depth, forming a receptacle for the bolted material. In this receptacle is provided a discharge-spout, E'. (Seen 5 in Fig. 3.)

At the top the machine is inclosed by a head, E³, corresponding in shape with the bottom board, E, and having also a rim, E², which depends far enough to form a suitable stop and to inner support for the removable outer inclosing walls or doors, D'.

F is a shallow circular receptacle having an inlet, F', through which the material to be separated is fed from the exterior of the machine. 15 Said receptacle F is secured in its position by attachment to the upright posts A³, as shown, or is otherwise supported.

At the upper end of the machine a rim or depending flange, F², corresponding in diameter with the top of the receptacle F, is secured in contact with the under surface of the head E³, either by attachment thereto or by attachment with the posts A³. The screen-frames C are continuous with this depending flange and 20 the upper margin of the receptacle F, so as to form a closed chamber, except that through the upper rim or flange, F², proceeds an outlet passage or spout, F³, for the discharge of the material not delivered through the 25 screen C. The upper surfaces of the horizontal ribs c' of the screen C are downwardly beveled, as indicated in Fig. 2, in order to allow the material discharged into the chamber D through the bolting-cloth to descend without 30 lodgment upon said ribs.

Concentric with the cylindrical screen or bolting-cloth C is located the drum B, which, for the purposes of this invention, may be either cylindrical, conical, or prismatic in form. Said 40 drum is mounted upon a vertical axial shaft, B', resting in a suitable foot-piece on one of the cross-beams a at the base of the machine, and rising through the supporting-block a' at the top, being provided with a suitable pulley 45 at either one end or the other, for its rotation by means of a belt leading from any convenient source of power. The drum B has its ends closed by suitable means, which may also serve to give attachment of the drum to the 50 shaft B' in any convenient or desirable manner.

Upon the exterior surface of the drum are attached beater-blades or wings B⁴. Said beater-blades may be either movable, so as to 55 permit change of their vertical direction, or they may be fixed; but in case they are immovably fastened to the drum an inclination will preferably be given them, somewhat as shown in Fig. 1, albeit, by means of devices to 60 be hereinafter described, an effective operation of the machine may be obtained if said drum-beaters are secured in a perfectly vertical position to the drum.

B⁴ B⁴ are blades arranged in a series upon 65 the inner surfaces of one or both of the posts A³. These blades B⁴ are pivotally secured at their middle points in the median line of said

posts A³, and are contrived to be held at any desired inclination or position. In the present instance, and as a preferable construction, 70 the pivot of each of the blades B⁴ consists of a rod, b, rigidly fastened at one end to the middle point of the blade, as shown in Fig. 8. Said rod is made of proper length to extend through the adjacent parts of the machine-frame, as seen in Figs. 3, 4, and 5, and at its outer or protruding end is provided with means, preferably in the nature of a cross bar or arm, b', by which the rod b may be rotated to give the desired inclination to the blade B⁴. 80 The cross bar or arm b' should be secured to the said rod in the same plane with the blade B⁴ within the machine, in order that the former may indicate to the eye the position of the latter. The blades B⁴ are desirably of 85 length equal to or a little wider than the faces of the parts A³, and, in case they are longer than the width of said parts, may be cut away at their ends or corners, as indicated, so that when turned in a horizontal direction they 90 will not injure the screen-cloth over which they will then project. Their edges adjacent to the drum may be slightly concaved throughout their length, in order to conform somewhat with the direction of the revolving 95 blades B³, which should run as nearly as possible or convenient to the stationary blades.

The adjustable blades B⁴ are the means relied on to vary or regulate the progress of the material upward through the machine. Such 100 material will, obviously, be thrown in a tangential direction from the beaters B³ by the revolution of the latter, and this course of the stuff will, as it strikes the blades B⁴ and the face of the post A³, carry it longitudinally of 105 said blades B⁴. By setting the latter in a properly-inclined position, therefore, the stuff will leave the blades at a higher point in the machine than that at which it strikes them. Encountering the screen after leaving the 110 blades, the stuff rebounds, and is caught by the beaters and is again thrown outward. When it falls upon another of the blades B⁴, it is again raised, and ultimately, by a succession of these operations, reaches the top of the 115 machine, whence it is discharged through the spout F³. A more or less rapid vertical movement of the stuff through the machine will therefore obviously be produced by a variation of the inclination of the blades B⁴, 120 or by rotation of the rods b, to which they are attached by means of the external devices, b'.

For the purpose of securely setting the said blades at any inclination given them the protruding parts of the rods b may be screw-threaded and provided with set-nuts b', arranged to bear on the outer surface of the frame, as shown in Figs. 2 and 5.

All of the blades B⁴ on one side of the machine may be simultaneously operated or 130 changed by means of a vertical rod, B⁵, pivotally connected with the several lateral arms b', as shown at the right in Fig. 1 and on both sides in Figs. 3 and 4. For the purpose of

also holding or securing the entire series of adjustable blades by a single device in this last-described construction, B⁶ is a bracket secured to the frame by bolts b⁵, and provided with a slot, b⁶, in the direction of the arms b', through which slot the connecting - rod B⁵ passes. For a suitable distance adjacent to and above and below this bracket the said rod is screw-threaded, and is provided with two 10 clamping-nuts, b³ b⁴—one above and one below the bracket. On desiring to lower the rod the upper nut is retracted, the rod is let down, and the lower nut is then run up against the bracket. To raise the rod the operation of 15 the nuts is reversed.

Obviously an inclination of the beaters B³ on the drum will give an upward movement of the material through the machine, and the minimum speed of such movement may be provided 20 for by such inclined position of said beaters, the variable increase of the upward movement being effected by the adjustable inclination of the stationary blades B⁴.

An important advantage of the construction 25 shown is found in the possibility of effecting the regulation desired without opening or stopping the machine.

By reference to Fig. 4 it will be seen that the lower ends of the lowermost drum-beaters B³ 30 are bent at b', so as to act as scoops running near the bottom of the receptacle F, and thereby lifting the material from said receptacle.

I do not wish to be limited to the particular 35 features of the construction herein shown with respect to the form of the frame or of the drum, since, so far as the frame is concerned, it is only necessary that stationary parts thereof or applied thereto shall be arranged in position to sustain the stationary adjustable blades B⁴.

40 In the accompanying drawings two sets or series of said blades are indicated. There may obviously be only a single series, or more than two, if desired. Said blades need not, also, be arranged in series, as shown, one above the

other, but may be set laterally out of line with 45 each other. The construction shown in this respect is, however, favorable to the application of the rod B⁵ for the simultaneous operation of the blades belonging to a single series.

I claim as my invention—

1. In a centrifugal bolt having a vertical axis and constructed to carry the material upward, the combination, with a rotating drum provided with beaters, of a surrounding screen and adjustable stationary blades, substantially 55 as described.

2. In a centrifugal bolt having a vertical axis and constructed to carry the material upward, the combination, with a rotating drum provided with beaters, of a surrounding screen, 60 pivoted stationary blades set edgewise to the drum and at a distance from the beaters thereon, and means constructed to adjust the said pivoted blades from the exterior of the machine, substantially as described.

3. In a centrifugal bolt having a vertical axis and constructed to carry the material upward, the combination, with a rotating drum having beaters thereon, of a surrounding screen, stationary blades set edgewise to the 70 drum, but clear of the beaters thereon, pivoted rods secured to said blades passing through the stationary part of the machine, and means exterior to the machine for rotating said rods, substantially as described.

4. The combination, with a rotating drum, B, and receptacle F, of the straight beaters B³, attached to the drum, having their lower ends bent in the direction of their motion, substantially as described.

In testimony that I claim the foregoing as my invention I affix my signature in presence of two witnesses.

LOUIS GATHMANN.
